UNITED STATES PATENT OFFICE.

HERMAN H. DIEHL, OF HUNTINGTON, WEST VIRGINIA, ASSIGNOR TO THE WEST VIRGINIA RAIL COMPANY, OF HUNTINGTON, WEST VIRGINIA, A CORPORATION OF WEST VIRGINIA.

SWAGING MACHINE.

Application filed May 8, 1924. Serial No. 711,811.

To all whom it may concern:

Be it known that I, HERMAN H. DIEHL, a citizen of the United States, residing at Huntington, in the county of Cabell and 5 State of West Virginia, have invented a new and useful Improvement in Swaging Machines, of which the following is a specification.

My invention relates, more particularly, 10 to a machine for forming railway frog-points formed from a bar of a cross sectional shape corresponding with a rail, a section of rail being preferably used, and bent upon itself whereby the diverging arms of the 15 frog-points are integral with each other at the apex of the point.

My primary object is to provide a machine whereby the rail, in bent condition, may be swaged into the desired form to 20 form the frog-point, and preferably given substantially its final shape.

I have devised my invention for use more particularly, though not to the exclusion of other uses, in the production of frog-points 25 of the construction disclosed in my pending application for U. S. Letters Patent Serial No. 666,009, filed October 1, 1923.

The frog-point of the application just referred to is of a construction wherein the 30 webs of the diverging arm portions, at the portions thereof adjacent the apex of the frog-point are less divergent than the remaining portions thereof, and to produce this condition the inner flange of the rail 35 from which the frog-point is to be formed is cut away to present a recess the divergent walls of which are less divergent at their outer extremities than at the portions thereof nearest the web of the rail. Thus in 40 forming a frog-point from such a rail, it is necessary that pressure be applied against the sides thereof, in the forming operation, to inwardly deflect, at both sides of the rail, the web portions thereof adjacent the junction 45 of the walls of the recess referred to and varying in divergence, as stated; and in this connection, another object of my invention is to provide a machine whereby the frog-point may be formed from a rail preliminarily shaped as stated.

Referring to the accompanying drawings:

Figure 1 is a view in side elevation of a machine constructed in accordance with my

invention. Figure 2 is a plan sectional view 55 of the machine taken at the line 2 on Fig. 1 and viewed in the direction of the arrow. Figure 3 is a plan view of the machine showing a frog point therein and the positions occupied by the parts of the machine 60 upon the conclusion of the swaging operation. Figure 4 is a plan view of the rail blank from which the frog point is to be formed, the blank being shown in the condition into which it is bent preliminarily to 65 its introduction into the machine. Figure 5 is a plan view of the frog point as produced by the machine. Figure 6 is a section taken at the line 6 on Fig. 1 and viewed in the direction of the arrow. Figure 70 7 is a section taken at the line 7 on Fig. 1 and viewed in the direction of the arrow. Figure 8 is a plan view of the blank shown in Fig. 4, before it has been bent to the 75 shape shown in the last referred to figure. Figure 9 is a broken section taken at the irregular line 9—9 on Fig. 3 and viewed in the direction of the arrow. Figure 10 is a broken section taken at the line 10—10 on Fig. 3 and viewed in the direction of the 80 arrows. Figure 11 is a broken sectional view taken at the line 11 on Fig. 3 and viewed in the direction of the arrow. Figure 12 is an enlarged, broken, plan sectional view taken at the line 12 on Fig. 10 and viewed in the direction of the arrow. Figure 13 is a broken sectional view taken 85 at the line 13 on Fig. 12 and viewed in the direction of the arrow; and Figure 14, an inner edge view of the pair of jaws forming 90 parts of the machine.

As a preface to the following description of the parts of the machine, and the manner in which the latter operates, it may be stated that the production of a frog-point of the particular construction hereinabove referred to involves the provision of a rail, or similar body, which is preliminarily mutilated at portions thereof to cause it to present the form shown in Fig. 8, the head 15 of the rail at opposite sides thereof and one base flange of the rail, being cut away at points midway between the ends of the rail, as represented at 16, 17 and 18, respectively, these cut away portions presenting the converging surfaces as represented at 19, 20 and 21, respectively, the points at which the converging surfaces 19 and 20 intersect ly-

ing in the same plane transversely of the rail, as shown, and the surfaces 19 being more divergent than the surfaces 21.

Referring now to the machine illustrated 5 in the drawings, the machine comprises a base-portion 22 presenting a flat, table-like, portion 23. Superposing the table top 23 is a pair of lever-members 24 and 25 pivotally connected together by a pivoting pin 10 26 passing through both of these members, between the ends thereof, and mounted at its opposite ends, respectively in the base 22 and in a yoke 27 secured to the table top 23 as by the screws 28. The lever-members 15 24 and 25 which are disposed at opposite sides of the axis of the pivot 26, as shown, present the jaws 29 and 30 by which, in the operation of the machine, the blank, from which the frog-point is to be formed, is 20 swaged into the desired shape, it being understood that these jaws are divergent and are capable, by reason of the pivot 26 of being swung back and forth relative to each other, the power, for operating these jaws as 25 stated, in accordance with the preferred illustrated embodiment of my invention, being applied to the ends of the lever-members 24 and 25 at the side of the pivot 26 opposite that at which the jaws extend, as 30 hereinafter described.

The inner faces of the jaws 29 and 30 at which portions the frog-point blank, to be swaged into the desired shape, is engaged, are directly opposed, as shown, and as a desirable arrangement for causing the machine to present the condition just referred to and provide for the location of the lever-members 24 and 25 at opposite sides of the axis of the pivot 26, the lever-member 25 35 at the portion thereof through which the pivot 26 extends, is formed with the vertically spaced, parallel, plate portions 31, which project laterally therefrom and form a bifurcation, the lever-member 24 being 40 provided with a circular disk-like portion 32 which is located within the space afforded between the parts 31 of the lever-member 24, the pivot 26 extending through the parts 31 and 32, as shown.

50 The means shown by which the jaws 29 and 30 are moved toward and away from each other, comprise links 33 and 34 pivotally connected, at 35 and 36 respectively, with the ends of the lever-members 24 and 25 opposite those affording the jaws 29 and 30, the links 33 and 34 which are arranged in overlapping relation at their inner ends (Fig. 6) containing circular openings 37 and 38, respectively, extending therethrough and in which eccentrics 39 and 40 rigidly secured to the upper end of a vertical shaft 41, are journaled, respectively, the eccentrics 39 and 40 being disposed 180° apart. The shaft 41 is journaled at its upper end in a yoke 42 rising from, and secured to, the

table-portion 23 of the machine, as by screws 43, and is journaled at its lower end in the base 22 of the machine, which latter is recessed around the shaft 41, as illustrated at 44. Any suitable means for driving the shaft 41 may be provided, those shown being of a more or less conventional type and providing for the automatic stopping of the machine upon the completion of a single rotation of the shaft 41. The mechanism 70 shown comprises a bevel-gear 45 located in the recess 44 and journaled on the lower end of the shaft 41, this gear meshing with a bevel-pinion 46 carried by a shaft 47 journaled in the base-portion of the machine 75 and driven from any suitable source of power. The bevel-gear 45 carries one of the co-operating elements of a clutch device, the other co-operating element of which is a sliding clutch sleeve 46a splined 80 to the shaft 41, as indicated at 47a. The interengaging portions of the clutch elements referred to comprise clutch teeth 48 and 49 provided on the gear 45 and the sleeve 46a, respectively, and adapted to mesh to drive 85 the shaft 41 from the gear 45 when the sleeve 46a lowers from the position shown in Fig. 6. A coil spring 50 surrounding the shaft 41 and bearing at its outer end against the upper wall of the recess 44 and at its lower 90 end against the top of the sleeve 46a operates to force the sleeve 46a into clutching engagement with the bevel-gear 45 under the control of clutch positioning mechanism 95 comprising a cam 52 provided on the underside of a continuous flange 53 on the sleeve 46a, and a sliding pin 54 reciprocable in an opening 55 in the base of the machine and adapted to normally assume the inwardly projected position shown in Fig. 6 under 100 the action of a coil spring 56 confined between a head 57 on the pin 54 and a plug 58 secured in the base at the outer end of the recess 59 in which the spring 56 is located, the pin 54 sliding in this plug. As 105 is common in machines comprising mechanism of the general character now being described for automatically stopping the rotation of a shaft after it has made one complete rotation, the cam 52 occupies a small 110 portion only of the circumference of the flange 53, and the pin 54 in normal position extends inwardly beyond the outer surface of the flange 53, the parts being so constructed and arranged that when that portion of the flange 53 which is unprovided with the cam, extends opposite the pin 54, the spring 50 is free to force the sleeve 46a into clutched 115 relation with the clutch member on the gear 45, but when the underside of the cam 52 rides upon the pin 54, the sleeve 46 will be raised, against the action of the spring 50, to a position in which this sleeve is unclutched from the gear 45. The pin 54 is 120 associated with operating mechanism com- 125

prising a bell-crank lever 60 fulcrumed at 61 on the base of the machine, one arm of this bell-crank being pivotally connected at 62 with the outer end of the pin 54 and its 5 other arm being pivotally connected at 63 with the upper end of a link 64, the lower end of which latter is pivotally connected at 65 with one end of a lever 66 fulcrumed at 67 on the base of the machine. The opposite 10 site end of this lever is in the form of a treadle 68, and a coil spring 69 connected with the base 22 of the machine and with the lever 66 operates to yieldingly rock the lever 66 in clockwise direction in Fig. 1, or 15 in other words in a direction tending to force the pin 54 inwardly.

The inner, opposed, portions of the jaws 29 and 30 are in the form of removable blocks 70 shown as provided on their outer 20 faces throughout a portion only of their length, with ribs 71 which fit into recesses 72 in the body-portions of the jaws, to which latter the blocks 70 are rigidly secured, as by the bolts 73. The opposing inner faces of 25 the blocks 70 are of a cross-sectional shape corresponding with one-half of the cross-sectional contour of the rail, except the base flange thereof, as shown in Figs. 9 and 10, whereby the inner surfaces of the jaws conformingly 30 fit the sides of the rail to be swaged into the frog-point and extend part way over the head of the rail. The inner faces of the jaws are provided with bars represented at 74 which are secured thereto 35 as by the bolts 75 the heads 76 of which extend in interlocking relation with the walls of recesses 77 in the member 70, these recesses opening through the faces of the member 70 at longitudinally extending slots 40 78 through which the bolts 75 extend. Thus the bar 74 may be adjusted thereof along the jaw members to cause them to operate as stops for the rear ends of the divergent 45 arms of the deformed blank of Fig. 4, during the process of swaging the latter. The machine is also provided with a block 79 which is positioned to extend between the divergent arms of the deformed blank of Fig. 4, at the outer ends of the latter and 50 be held against displacement by interlocking, with the table-portion 23, this interlock, in the particular construction shown, being effected by providing the rod 80 which is carried by the member 79 and is adapted 55 to extend at its downwardly bent portion 81 into a recess 82 in the table top. The ends of the member 79 are shaped to cause them to conformingly fit against the inner, opposed, sides of the web-portions of the bent 60 rail and conformingly fit the upper surfaces of the adjacent base flanges and the under surfaces of the head-portions of the rail, as shown in Fig. 10.

A description of the operation of the machine is as follows, the machine being shown

in one of the positions it assumes while operating. Assuming that the machine is at rest, in which condition the cam 52 bears downwardly against the pin 54 directly beneath it and the sleeve 46^a is thus in raised 70 position and unclutched from the gear 45, in which position of the parts, the jaws 29 and 30 are swung outwardly to extend at a greater divergence relative to each other, than as shown in the drawings, the deformed blank 75 of Fig. 4, which is made from the mutilated rail section of Fig. 8, by preliminarily heating the rail at its central portion and bending it to the position in Fig. 4, is introduced into the machine to rest on the table top 23 80 between the jaws 29 and 30, with its outer extremities opposing the stop-forming ends of the bars 74, and the block 79 then applied to the machine to the position shown with its ends opposing the inner surfaces of the diverging arms of the deformed blank of 85 Fig. 4. The deformed rail having been introduced into the machine to the desired position, the operator presses downwardly on the treadle 68 thereby withdrawing the 90 pin 54 from engagement with the cam 52 with the result that the spring 50 forces the sleeve 46^a into clutched relation with the gear 45 and the shaft 41 is thereupon rotated, the shaft continuing rotation until it 95 has made one complete rotation, during which time the operator has released pressure on the treadle with the result that the pin 54 is in a position to oppose the cam 52 which latter in riding against the pin forces the sleeve 46^a out of clutching engagement with the gear 45. Rotation of the shaft 41, as stated, causes the levers 24 and 25 to rock on the pivot 26 in a direction to move the jaws 29 and 30 toward each other for 100 swaging the deformed blank of Fig. 4, into the condition shown in Fig. 5. It will be noted that in the structure shown in Fig. 5, the web-portions of the rail at the portions 105 thereof, represented at 83 are less divergent than the remaining portions thereof represented at 84, and that the edge-portions of the side flanges of the rail, and represented at 85, adjacent the apex portion, are less divergent than the remaining side portions thereof. This condition is produced by so shaping the inner, opposed, faces of the blocks 70 where they engage the web-portions and the side flange portions of the blank, as to exert a deflecting pressure against these parts 110 in the swaging operation, the feature of providing the surfaces 19 and 21 of varying convergence, as shown and described, permitting of the deflection of the webs and side flanges of the rail as shown and described, the opposed surfaces 21 and the opposed surfaces 19 in the formed structure of Fig. 5 being substantially in contact. 115

The effect of providing a machine as 120 stated, is to not only cause the arms of the 125

structure of Fig. 5 to present the desired divergence, but also causes the apex portion of the point to be formed as shown, due to the fact that the metal, at the apex portion of the structure being formed, is caused to be squeezed in a direction toward the axis of the pivot 26 resulting in the production of the desired pointed apex. The block 79 is of particular value where the webs and side rail flanges are to be deflected as shown in Fig. 5, as it serves as a stop gage, insuring the desired angle of divergence of the arms of the frog-point.

In the particular illustrated embodiment of my invention, the extent of the movement of the lever-members 24 and 25 toward and away from each other in the operation of the actuating means therefor, remains fixed, and thus to provide for the making of frog-points having different angles of divergence, it is necessary to provide different shapes and sizes of block 70, and different lengths of members 79, the arrangement shown permitting of the ready removal 23 from, and attachment to, the body-portions of the lever members 24 and 25, of the blocks 70 of any desired shape.

If desired the frog-point of Fig. 5 may be machined at its side flanges to cause its lateral converging edges to extend in alignment with the adjacent edges 86, instead of diverging therefrom as represented at 85. The opposed portions of the frog-point at the apex thereof may be secured together, if desired, in any desired manner, as for example by welding the mutually contacting surfaces of the frog-point either at its upper surface or lower surface, or at both surfaces and if desired the frog-point may be formed 40 with a hard metal insert at its apex portion, as disclosed in my above referred to application.

While I have illustrated and described a particular construction embodying my invention, I do not wish to be understood as intending to limit it thereto as the same may be variously modified and altered without departing from the spirit of my invention.

What I claim as new, and desire to secure by Letters Patent is:

1. A swaging machine comprising a pair of relatively movable jaws, means for effecting movement of said jaws to cause the same to approach each other in converging relation to engage and shape a frog-point blank disposed between the same, and means adapted to engage the outer ends of the frog-point blank to prevent rearward movement of the blank.

2. A swaging machine comprising a pair of relatively movable jaws, means for effect-

ing movement of said jaws to cause the same to approach each other in converging relation to engage and shape a frog-point blank disposed between the same, and means on 65 said jaws adapted to engage the outer ends of the frog-point blank to prevent rearward movement of the blank.

3. A swaging machine comprising a pair of relatively movable jaws, means for effecting movement of said jaws to cause the same to approach each other in converging relation to engage and shape a frog-point blank disposed between the same, means adapted 70 to engage the outer ends of the frog-point blank to prevent rearward movement of the blank, and means, stationary relative to said jaws and spaced therefrom, for engaging the inner surfaces of the article to be swaged and gaging the angle at which the 75 arm portions of the frog-point diverge.

4. A swaging machine comprising a pair of relatively movable jaws, means for effecting movement of said jaws to cause the same to approach each other in converging relation to engage and shape a frog-point blank disposed between the same, and means adapted to engage the outer ends of the frog-point blank to prevent rearward movement of the blank and force the metal of 80 the blank forwardly into the apex portion of the jaws.

5. A swaging machine comprising a pair of pivoted jaws, means for producing relative movement of said jaws about said pivot 85 to cause said jaws to approach each other in converging relation to engage and shape a frog-point blank disposed between the same, the working faces of said jaws converging toward the axis upon which said jaws are pivoted and being so disposed that the planes in which they extend intersect short of said axis, and means adapted to engage 90 the outer ends of the frog-point blank to prevent rearward movement of the blank.

6. A swaging machine comprising a pair of pivoted jaws, means for producing relative movement of said jaws about said pivot to cause said jaws to approach each other in converging relation to engage and shape a frog-point blank disposed between the same, the working faces of said jaws converging toward the axis upon which said jaws are pivoted and being so disposed that the planes in which they extend intersect short 100 of said axis, and means adapted to engage the outer ends of the frog-point blank to prevent rearward movement of the blank and force the metal of the blank forwardly 105 into the apex portion of the jaws.

HERMAN H. DIEHL.
